CLAIM

The ornamental design for a medical pad for ultrasonically activated device, as shown and described.

DESCRIPTION

FIG. 1 is a front, top, left-side perspective view of the medical pad for ultrasonically activated device;

FIG. 2 is a rear, bottom, right-side perspective view thereof;

FIG. 3 is a front elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a reference view showing the pad in a state attached to the device.

The broken lines depict environmental subject matter only, and thus form no part of the claimed design.
